UNITED STATES PATENT OFFICE.

ORANGE J. SALISBURY, OF SALT LAKE CITY, UTAH.

CONTINUOUS PROCESS APPARATUS FOR FORMING ARTICLES FROM PULP.

Original application filed September 13, 1921, Serial No. 500,300. Divided and this application filed July 24, 1923. Serial No. 653,409.

The present invention relates to improvements in apparatus for filtering and forming articles from pulp solutions and more especially to continuous process apparatus 5 for forming articles from pulp.

It is the object of this invention to provide means whereby articles may be automatically formed and discharged complete, directly from a pulp solution whereby the 10 manufacture of such articles may proceed indefinitely, so long as power and materials be supplied, with a uniform quality of product and with a minimum of attention.

The present application is a division of 15 my application entitled "Apparatus for filtering and for forming articles from pulp solutions", filed September 13, 1921, Serial No. 500,300 patented May 12, 1925 as Patent Number 1,537,195.

20 Like numerals have been employed to indicate like parts throughout the several views of the drawings, in which;

Figure 1 is an elevation in partial section of one preferred embodiment of my invention;

Figure 2 is a sectional view of the device shown in Figure 1, taken on the line 2—2, of that figure;

Figure 3 shows in detail one portion of 30 the device shown in Figure 1;

Figure 4 serves to show a further detail; and

Figure 5 illustrates a third detail of construction.

35 In Figure 1 of the drawings a suction filter drum 10 is supported upon the hollow shaft 12 which revolves in the bearings 14 supported in the frame 16. The frame 16 also serves to support the pulp vat 20 and the hood 21 which is provided with side openings to permit the entrance and exit of 40 the web or belt 22. This belt partially encircles the drum 10 and passes out through the extension 23 of the casing, hood 21, to a discharge point 25. From this point, after 45 passing over the idler roller 26 and a guide roller 28, it again enters the hood 21 and returns to the drum 10. Belt 22 carries upon 50 its surface a series of moulds 30, best seen in Figure 5, which move with the belt and are supported thereby.

The drum 10 has upon its outer surface a series of openings 33 which communicate, through such means as the tubes 35, with the interior of the hollow shaft 12 and there-

through to a suction connection 38 which leads to any suitable suction source, not shown. Drum 10 is secured to and revolves with the shaft 12 which is rotated through such means as the gearing 40 from a suitable power source 41. It will be seen that no valve gear of any sort is contained in the shaft 12 or in the suction connection 38 and that all of the openings 33 are subjected to an equal suction irrespective of the rotation of the shaft or drum. Drum 10 is arranged over and dipping into the pulp vat 20 in such manner that a substantial portion of its surface is submerged in the pulp solution 40 contained in the vat.

The belt 22 is constructed from such easily permeable material as screen or fabric which has sufficient mechanical strength to support and guide the moulds 30, without being of such great weight that it must be 75 supported at the frequent intervals necessary to the chains formerly employed in attempts to produce continuous operation.

The fabric has the added advantages that the moulds can be supported every few 80 inches and need therefore have no heavy castings or reinforcements. In fact, it is permissible and preferable that the moulds be constructed, as in Figure 5, of light filter fabric or screen, and that the moulds will always lie evenly upon the suction drum 10 as the suction from the openings 33 acts through the belt 22 and holds it in positive contact with the drum surface. This positive contact between the belt 22 and drum 10 aids the drum in driving the belt and also assures a seal between the mould edges and the drum, to insure proper tracking of the belt upon the drum and as a further aid to driving it has been found preferable in some cases to provide lugs 43 upon the drum which mesh with openings 44 in the belt edge. The tension of belt 22 is positively adjusted by means of the bearings 45 of the shaft carrying the idler roller 26, and such adjustment may be made while the machine is in operation, if desired.

In operation, the pulp vat 20 is maintained partially full of pulp in solution as is indicated in Figure 2, the drum 10 is slowly rotated driving the belt 22 while suction is applied through the connection 38. The movement of the belt 22 immerses the moulds 30 as it passes under the drum 10 in the pulp solution 40, the suction acting through the

shaft 12, the tubes 35, the belt 22 and the moulds 30 rapidly deposits the pulp from the solution upon the mould surfaces while the solution liquid passes to the suction connection 38. Further movement of the belt 22 carries the moulds above the surface of the pulp solution and air from the interior of the hood 21 is drawn through the pulp which has been deposited upon the moulds 5 thus drying it. To aid in rapid drying, heating coils 50 may be employed to raise the temperature of the air which is drawn through the deposited pulp, and these coils may be supplemented by direct heating coils 10 51 when a product requiring still faster drying is to be produced. As the product dries the onward movement of the belt carries it to the discharge point 25 where the passage of the belt around the idler roller 26 inverts 15 the moulds, and because of the greater radius of curvature to which the mouths of the moulds must conform in passing over this relatively small diameter roller, the mould mouths are stretched and the product readily 20 25 frees itself for discharge to such means as the conveyor 53, or to such other disposal of the complete product, as may be most suitable to the conditions existing in a given manufacturing plant.

30 From the point of discharge 25 the now empty moulds are carried by the belt back to the pulp vat, and it has been found advantageous to interpose a cleaning device 60 in this return path, thus assuring clean, free 35 moulds and a uniform product even after long periods of operation. The cleaning device is shown in detail in Figure 4 of the drawings and in its simplest form comprises a revolving brush 62, a spray 63 and a catch 40 basin 64 draining through the pipe 65 to the sewer or other suitable discharge point. The brush 62 is preferably a long bristle one revolving at a considerable speed so that it may reach and cleanse the innermost corners 45 of the moulds, as an aid to such cleansing a spray jet 66 directed through the belt and moulds has also proved efficacious. The action of this cleanser is of course entirely automatic and is a continuous after the machine is once started.

It has also been found an advantage to provide a shield 70 arranged close to that portion of the surface of the suction drum 10 which the belt 22 does not cover, this shield 55 serving to prevent the in-rush of air to the openings 33 which would otherwise occur and thus reduce the work required of the suction producing means, while still removing the need of a valve in the drum or 60 drum-shaft, as has been previously pointed out.

It will be seen that the herein described mechanism involves no intricate parts nor is the complete apparatus of such nature that it 65 may not be operated by other than expert me-

chanics, but that it is adapted for installation and maintenance without the expenditure of any considerable amount of skill or engineering materials. The web or screen belt employed reduces very considerably the weight of the complete apparatus, reduces the weight and strength of moulds required while permitting the widest possible range of mould form. This belt also insures sealing between the moulds and suction drum 75 and an even distribution of the suction over the mould surface together with a positive driving contact with the surface of the suction drum. The cleaning device which has been described may be replaced in whole or 80 in part with other suitable mechanism, and with some pulp ingredients removed entirely as the mould movement in passing over the idler and guide rollers will free the moulds without aid. It should be understood, however, that the binders employed and the nature of the pulp fibers, ordinarily demands the use of a cleaner.

It will also be understood that many changes and modifications may be made in 90 the embodiment of my invention, that various parts may be employed for the accomplishment of beneficial results without the employment of other parts, and that while I have illustrated and described the best forms 95 of my invention now known to me, it will be apparent to those skilled in the art that changes may be made without departing from the spirit of my invention or the scope of the appended claims.

What I claim is:

1. In a pulp forming and moulding apparatus, a suction drum and a mould carrying belt, said belt adapted to make tight contact with said drum and to transmit suction therefrom to the aforesaid moulds.
2. In a pulp forming and moulding apparatus, a suction drum having a substantially regular periphery, a mould structure having an irregular surface, and a belt, said belt adapted to carry the mould structure and to fit the periphery of the said suction drum.
3. In a pulp forming and moulding apparatus, a suction drum having a substantially regular periphery, a mould structure having an irregular surface, and a permeable web, said web attached to the irregular surface of said mould structure but sufficiently flexible to engage the periphery of the said suction drum for the purpose of transmitting suction from said drum to said mould structure.
4. The means for forming a suction tight connection between moulds of irregular form, and a suction surface of regular form, which comprises a movable permeable web upon one side of which the moulds are mounted and the reverse side of which is applied to the suction surface.

5. A continuous moulding surface for a continuous process moulding machine comprising a plurality of irregular moulds formed from permeable material and 5 mounted upon a flexible permeable web.
6. In a pulp forming and moulding apparatus comprising a belt carrying foraminous moulds, the means for ejecting articles from said moulds which comprises a roller 10 of small radius around which the said belt may pass to temporarily distort the said moulds.
7. In a machine of the character described, a tank adapted to contain a pulp 15 solution, a drum arranged to rotate with a portion of its periphery submerged in the solution, said drum being provided with means for applying suction inward from its periphery, and a belt carried filtering 20 medium movable within the tank in contact with said drum and without the tank out of contact with said drum, said filtering medium being shaped to conform to the articles which it is desired to produce.
- 25 8. In a machine of the character described, a tank adapted to contain a pulp solution, a drum arranged to rotate with a portion of its periphery submerged in the
- solution, said drum being provided with means for applying suction inwardly from 30 its periphery, a filtering medium in belt form shaped to conform to the shape of the articles being produced movable within the tank in contact with said drum, and without said tank out of contact with the drum, means for supporting said filtering medium so as to act as a conveyor to carry the deposited material away from the drum, and means for heating said filtering material and the material deposited thereon during 35 40 its movement away from the drum.
9. In apparatus for forming articles from pulp solutions, a pulp tank, a suction drum, a permeable belt, foraminous moulds, a 45 drier, a discharger, and a mould cleaner, said pulp tank adapted to contain a pulp solution with a portion of the said drum immersed therein, said permeable belt adapted to carry the said foraminous moulds into said tank around the said drum through the said solution and through said drier to the discharger thence to the cleaner and back to the aforesaid tank.

In testimony whereof I have affixed my signature to this specification.

ORANGE J. SALISBURY.
